UNITED STATES PATENT OFFICE.

JOHN H. HUHN, OF FAIRMONT, WEST VIRGINIA, ASSIGNOR OF ONE-FIFTH TO MARY HUHN, OF FAIRMONT, WEST VIRGINIA.

LOADING APPARATUS.

1,293,447.

Specification of Letters Patent.

Patented Feb. 4, 1919.

Application filed February 8, 1918. Serial No. 216,063.

To all whom it may concern:

Be it known that I, JOHN H. HUHN, a citizen of the United States of America, and resident of Fairmont, county of Marion, and 5 State of West Virginia, have invented certain new and useful Improvements in Loading Apparatus, of which the following is a specification.

This invention relates broadly to loading 10 apparatus, and more specifically to a power-driven shovel and conveyer for loading coal and like materials in cars or the like.

The primary object of the invention is to provide an efficient apparatus whereby materials, such as coal, may be rapidly loaded 15 upon cars for transportation, and which is especially adapted for use in mines.

A further object is to provide a power-driven apparatus of the character mentioned 20 which is automatic in its operation, which is strong and durable in its construction, having but few parts liable to become out of order, and which may readily be shifted from place to place as occasion requires.

25 With these and other important objects in view, the invention resides in the features of construction, arrangement of parts and combinations of elements which will herein-after be exemplified, reference being had to 30 the accompanying drawings, in which—

Figure 1 is a side elevation of the invention;

Fig. 2 is a front end elevation;

Fig. 3 is a rear end elevation;

35 Fig. 4 is a top plan view;

Fig. 5 is an enlarged section taken substantially on line 5—5, Fig. 4;

Fig. 6 is a side elevation of the front end portion of the machine, showing various positions assumed by the shovel; and—

40 Fig. 7 is an enlarged detail section of the reversing gear.

Referring to said drawings, in which like designating characters distinguish like parts 45 throughout the several views—

1 indicates a large gear which is mounted horizontally beneath the upper part, as the platform 2, of a truck-carried frame, said gear being keyed or splined upon and rotatable with an upright pin or shaft 3 which has its lower end suitably disposed, as in a portion 4 of the truck frame which underlies said gear 1, the latter being spaced away from said portion 4 and supported by a 50 suitable bearing-like washer 5 within which

said shaft 3 is rotatable. Said gear has a long hub 6 which projects upward a considerable distance above the level of said platform 2, and attached to the end of said shaft 3 which projects from said hub and 60 resting upon the end of the latter is one end of a crank-arm 7 which has its opposite end pivotally connected to the rear end of a connecting rod or pitman 8 which has its front end connected pivotally to a horizontally 65 disposed carriage 9. The crank-arm 7 is interlocked with said hub 6 in a suitable manner, as by a downwardly projecting stud or pin 10 carried by said arm and seated in a socket 11 provided therefor in the end of 70 said hub.

Said carriage 9 is longitudinally slidable over parallel gibs 12 or upon the front end of an underlying turn-table 13 which carries said gibs. Said turn-table overlies and has 75 rotary movement upon or with respect to a plate or table 14, herein depicted as of circular form, which is rigidly mounted upon the truck platform 2. Said turn-table has a downwardly-extending hub 15 disposed for 80 rotary movement about the hub 6 of gear 1.

The carriage 9 is disposed between said gibs 12 which have their opposing faces undercut to form guideways 16 in which portions of said carriage are received, tipping 85 or overturning movement of said carriage being thus effectually prevented.

Mounted upon said carriage 9 are suitable bearings, as 17, in which is journaled a transverse shaft 18 having fixed on its opposite ends wheels 19 adapted to travel back and forth, with reciprocating motion of said carriage 9, upon trackways 20 carried by or formed by said turn-table 13 adjacent to the lateral edge of the latter. Said wheels have 95 spurs 19^a disposed about the periphery thereof, which engage with alined seats or holes, 21 provided in said trackways 20, whereby positive traction is afforded for effecting rotation of said wheels. 100

Extending diametrically across the outer face of each wheel 19 and either fixed to or formed integral with such wheel is a cross-head or crank 22 which carries at one end a crank-pin 23 upon which is pivoted the rear 105 end of an arm 24. The front ends of the opposite arms 24 are pivotally mounted upon trunnions 25 carried by the opposite sides 26 of a shovel or scoop which is generally designated by the reference letter A and which 110

has a bottom 27 and a back 28 disposed approximately at right angles to each other, as shown.

Disposed in meshing relation to the gear 1 is a pinion 29 fixed upon an upright shaft 30 journaled in suitable bearings carried by the frame and in an upright sleeve-bearing 31 mounted upon the top of said frame. Fixed upon the upper end of said shaft 30 is a bevel-gear 32 adapted to be operatively engaged by one or the other of two oppositely facing bevel-gears 33 and 34 according as it is required to drive said shaft in one direction or the other. Said gears 33 and 34 are fixed upon a shiftable sleeve 35 and are spaced apart such a distance that they cannot simultaneously engage the bevel gear 32. Said sleeve 35 is keyed upon and shiftable along a transverse shaft 36 journaled in suitable bearings, as 37, carried by upright frame members 38 mounted upon the platform 2 or other suitable portions of the truck frame. A spur gear 39 carried by said shaft 36 has disposed in driving relation thereto a pinion 40 carried by the drive-shaft of an appropriately located electric motor 41.

Associated with the sleeve 35 is suitable means, as the connected pivotally mounted lever members 42 and 43, whereby shifting of said sleeve in either direction may be accomplished.

Disposed in a suitably elevated position, as upon the frame members 38, are the side members of a rectangular box-like inclosure 44^a constituting a part of a conveyer which is herein designated generally by the numeral 44. Said conveyer has the forward portion thereof disposed in overhanging relation to the truck platform 2 and to part of the hereinbefore described mechanism carried by said platform, and the rear end of said conveyer extends rearward from its supports and with respect to the rear end of the truck by which said supports are carried, so that it may occupy a position overlying or overhanging a car or the like to be loaded, as is best shown in Fig. 1. A plurality of transverse rollers 45 are located within the inclosure 44^a, the same having their shafts suitably journaled, as in the side members of said inclosure. Mounted on said rollers to be actuated by the latter is an endless traveling conveyer or apron 46 upon which the material being loaded is dumped from the shovel and by which said material is carried rearward and dumped into a car overhung by the rear end of said conveyer.

Power for producing travel of the apron 46 may be applied in any appropriate manner, as by a sprocket chain 47 connecting a sprocket wheel 48 on the end of the shaft of one of the rollers 45 to a sprocket wheel 49 carried by the shaft 36.

65 For changing the direction of the thrust

of the shovel to any desired angle with respect to the longitudinal line of the machine, the turn-table 13 is made laterally shiftable. A worm-gear 50 is mounted to rotate on the hub 6 of gear 1 and is fixed to said turn-table, as by means of bolts 51. A worm 52 carried by a transverse shaft 53 is operatively engaged with said worm-gear. Said shaft is located rearward with respect to said worm-gear and is journaled in bearings, as 54, mounted on the truck platform 2. While said shaft may be driven in any suitable manner for accomplishing rotation of the turn-table for shifting the shovel laterally, I prefer to employ a sprocket wheel 55 located on said shaft, and to connect the same by means of a sprocket chain 56 to a sprocket wheel 57 which is rotatably mounted on an end of the shaft 36. Said sprocket wheel has a dentated hub 57^a adapted to be operatively engaged by a correspondingly dentated clutch-member 58 which is mounted on said shaft 36 and which is adapted to be shifted into and out of interlocking relation to said hub 57^a, as by means of a suitable lever 59. As is obvious, the direction of rotation of the turn-table 13 is controlled by control of the direction of rotation of the shaft 36.

In practice, when the shovel-operating motive power is applied, as when the electric motor 41 is started, the shaft 36 is driven through the pinion 40 and gear 39. The sleeve 35 is shifted to carry one or the other of the bevel gears 33 or 34 into meshing relation to the bevel gear 32 according as it is desired to rotate the shaft in a forward or reverse direction. As will hereinafter be explained, the shovel and its actuating mechanism are operable with equal facility irrespective of the direction of rotation of said shaft 36. Motion imparted to said bevel gear 32 is communicated through the shaft 30 and the pinion 29 to the large gear 1, thence through the hub 6 of the latter to the crank-arm 7, pitman 8 and carriage 9, the latter being actuated to move back and forth in a reciprocatory manner between the gibs 12 located on the front end of the turn-table 13. With such movement of the carriage 9, the wheels 19 travel back and forth upon the trackways 20, rotation as distinguished from sliding movement of said wheels being insured by the inter-engagement of the spurs 19^a thereof with the seats 120 or holes 21 provided in said trackways.

Rotation of said wheels 19 in a forward direction actuates the shovel A to advance, and vice versa. Forward rotation of said wheels following that in which the shovel initially seats upon the ground or floor, shown in full lines in Fig. 6, results in said shovel being advanced along said ground or floor to or toward the forward dotted-line position shown in said figure for scooping

up the material to be loaded. When the shovel has received its load, it is withdrawn from the bank or pile of material, actuated by rearward travel of the carriage 9 and the 5 wheels 19, until it reaches said initial seating position, whereupon the under sides of the inclined shovel arms 24 engage laterally projecting fulcrum-pins 60 carried by ends of the cross-head-like cranks 22 opposite the 10 ends thereof which carry the crank-pins 23. Continued rearward rotation of said wheels 19 results in said arms 24 and the loaded shovel being elevated from said initial shovel-seating position to the substantially 15 upright position shown in dotted lines in Figs. 1 and 6, and in full lines in Figs. 2 and 3. Slightly prior to said position being reached, an arm 61 carried by the back 28 of the shovel engages an arcuately curved out-standing horizontal member or rim 62 carried by the front end of the box-like inclosure 44^a of the conveyer, whereby said shovel is swung to the rearwardly tipped position shown for dumping its contents upon the 20 forward end of the apron conveyer 46 by which said contents are conveyed rearward, as hereinbefore described.

The final shovel-dumping position is assumed when the crank-arm 7 and the pitman 8 occupy their rearmost positions with the latter overlying and in parallel alinement with the former. Consequently, continued rotary movement of the last-mentioned parts serves to reverse the direction of movement of the carriage 9 and the wheels 19 whereby the shovel is returned to its initial seating position and is thence again thrust forward into the bank or pile of material, as aforesaid. Thus, as is apparent, uninterrupted operation, without reversal of the mechanism which effects reciprocation of the shovel - carrying mechanism is permitted. Further, when in the operation of the shovel, the same may be advantageously advanced 45 into the bank or pile of material to the limit of its forward movement, the reciprocation-producing mechanism may be driven uninterruptedly, or without reversal, it being obvious that, when the shovel has reached the 50 limit of its forward travel, the crank-arm 7 and pitman 8 occupy positions in extended alined relation, and that continued movement will act to return the shovel in rearward direction. However, when it is impracticable to advance the shovel to the limit of its forward movement, as when the bank or pile of material to be handled lies close to the initial shovel-seating position so that the shovel receives its load with a thrust short 55 of that of which it is capable—that is, with a fractional part of the possible thrust—the sleeve 35 is shifted on the shaft 36 in the manner hereinbefore indicated to effect a reversal of the direction of rotation of said shaft and, consequently, of the mechanism 60

intermediate said shaft and the carriage 9 for moving the latter rearward, thus accomplishing retraction of said shovel. Such reverse movement of said mechanisms will be continued until the shovel is again loaded, 70 whereupon the sleeve 35 may again be shifted to effect retraction thereof, and so on.

To prevent rearward tipping or dumping movement of the shovel while it is being retracted to the point where elevation thereof 75 begins, rearwardly extending bracing members, as 26^a, preferably constituting extensions of the shovel sides 26, are provided. On the other hand, to prevent forward tipping of the shovel which would result in discharge of its load during elevation thereof, fulcrum pins, as 63, are suitably located on said members 26^a for assuming underlying engagement with the shovel arms 24 at the moment when elevating movement commences. 85

Angular members or feet 64 are preferably carried by the rear ends of the shovel arms 24 in a position for seating upon the platform 2 to prevent rearward tilting movement of said arms beyond the requisite substantially upright position assumed by the latter when shovel-dumping position is reached. 90

As is obvious, the carriage 9 may be 95 wholly supported by the shaft 18 upon which the wheels 19 are mounted, or it may be supported by and have sliding movement on the gibs 12. In the latter case said wheels serve merely as shovel-actuating elements. 100

What is claimed is—

1. A loading machine comprising a truck frame, a carriage superposed on said frame, means for imparting reciprocating motion to said carriage, wheels carried by said carriage, trackways for said wheels, eccentrically disposed crank-pins carried by said wheels, arms pivotally mounted at their rear ends on said crank-pins, a shovel pivotally connected to said arms, and fulcrum pins 110 carried by said wheels and adapted to engage said arms for elevating the latter to substantially upright position. 105

2. A loading machine comprising a truck frame, a carriage superposed on said frame, 115 means for imparting reciprocating motion to said carriage, wheels carried by said carriage, trackways for said wheels, a shovel, arms pivotally connected at one end to said shovel and having their opposite ends 120 mounted eccentrically on said wheels, and means adapted to be engaged by said arms at a point in the travel of said wheels, whereon said arms and shovel are elevated to substantially upright position. 125

3. A loading machine comprising a truck frame, a carriage superposed on said frame, means for imparting reciprocating motion to said carriage, wheels carried by said carriage, trackways for said wheels, a shovel, 130

arms pivotally connected at one end to said shovel and having their opposite ends mounted eccentrically on said wheels, a conveyer, and interengaging means whereby 5 said shovel is actuated to dump its contents on said conveyer when said upright position is assumed.

4. A loading machine comprising a truck frame, a carriage superposed on said frame, 10 means for imparting reciprocating motion to said carriage, wheels carried by said carriage, trackways for said wheels, a shovel, arms pivotally connected at one end to said shovel and having their opposite ends 15 mounted eccentrically on said wheels, and means adapted to be engaged by said arms at a point in the travel of said wheels, whereon said arms and shovel are elevated to substantially upright position.

20 5. A loading machine comprising a truck frame, a carriage superposed on said frame, means for imparting reciprocating motion to said carriage, wheels carried by said carriage, trackways for said wheels, a shovel, 25 arms pivotally connected at one end to said shovel and having their opposite ends mounted eccentrically on said wheels, and fulcrum pins carried by said wheels for assuming underlying supporting relation to 30 said arms at an intermediate point in the rearward travel of said wheels and for elevating said arms thereon during continued rearward travel of said wheels, said crank pins and said fulcrum pins being 35 located in diametrically opposite relation with respect to said wheels.

6. A loading machine embodying a wheeled carriage, means for imparting reciprocating motion to said carriage, crank-pins carried 40 eccentrically by said wheels, a shovel having the front ends of carrying arms pivoted thereto, the rear ends of said arms being mounted on said crank-pins, fulcrum pins carried eccentrically by said wheels and 45 adapted to assume supporting engagement with said arms at an intermediate point in the rearward travel of said carriage, whereby said shovel is carried to and from elevated dumping position, said crank-pins and said 50 fulcrum pins being so located relatively that a long forward thrust and corresponding retraction of said shovel is permitted following the deposit of the latter on the ground.

55 7. A loading machine embodying a turn-table, means for imparting rotary movement to said table, a carriage mounted on said turn-table, means for imparting reciprocating motion to said carriage, a shovel having 60 the front ends of carrying arms pivoted thereto, rotary means intermediate said carriage and said arms whereby the latter are advanced and retracted, respectively, during the last half of the forward movement and 65 the first half of the rearward movement of

said carriage, and means carried by said rotary means whereby said arms are engaged and elevated to approximately upright position during the remainder of said rearward movement of the carriage and are 70 lowered to a position depositing the shovel on the ground during the first portion of the forward movement of said carriage.

8. A loading machine embodying a turn-table, means for imparting rotary movement 75 to said table, a wheeled carriage mounted on said turn-table, means for imparting reciprocating motion to said carriage, a shovel, means intermediate the wheels of said carriage and said shovel whereby the latter 80 is advanced and retracted, respectively, during the last half of the forward movement and the first half of the rearward movement of said carriage, means carried by said carriage wheels whereby said shovel and 85 said intermediate means are elevated to approximately upright position during the remainder of said rearward movement of the carriage and are lowered to ground-engaging position during the first portion of the 90 forward movement of said carriage, a conveyer, and means whereby said shovel is tipped to dump its contents on said conveyer when it assumes elevation position.

9. A loading machine comprising a 95 wheeled carriage, means for imparting reciprocating motion to said carriage, a shovel, means intermediate the wheels of said carriage and said shovel whereby the latter is advanced and retracted, respectively, during 100 the last half of the forward movement and the first half of the rearward movement of said carriage, and means whereby said shovel is elevated to approximately upright position during the remainder of said rearward 105 movement of the carriage and is lowered to ground-engaging position during the first portion of the forward movement of said carriage.

10. A loading machine comprising a 110 wheeled carriage, means for imparting reciprocating motion to said carriage, a shovel, means intermediate said carriage and said shovel whereby the latter is advanced and retracted, respectively, during 115 the last half of the forward movement and the first half of the rearward movement of said carriage, means whereby said shovel is elevated to approximately upright position during the remainder of said rearward movement of the carriage and is lowered to ground-engaging position during the first portion of the forward movement of said carriage, a conveyer, and means whereby 120 said shovel is tipped to dump its contents on said conveyer when it assumes elevated position.

11. A loading machine comprising a wheeled carriage, means for imparting reciprocating motion to said carriage, means 125

for effecting reversal of the first-mentioned means whereby said carriage may be reversed at any point in its reciprocating movement, a shovel, means intermediate said carriage and said shovel whereby the latter is advanced and retracted, respectively, during the last half of the forward movement and the first half of the rearward movement of said carriage, and means whereby said shovel is elevated to approximately upright position during the remainder of said rearward movement of the carriage and is lowered to ground-engaging position during the first portion of the forward movement of said carriage.

12. A loading machine comprising a constantly rotated crank arm, a wheeled carriage, a pitman intermediate said crank arm and said carriage whereby uniform reciprocating movements are imparted to the latter, a shovel, means intermediate said carriage and said shovel whereby the latter is advanced and retracted, respectively, during the last half of the forward movement and the first half of the rearward movement of said carriage, means whereby said shovel is elevated to approximately upright position during the remainder of said rearward movement of the carriage and is lowered to ground-engaging position during the first portion of the forward movement of said carriage, a conveyer, and means whereby said shovel is tipped to dump its contents on said conveyer when it assumes elevated position.

13. A loading machine comprising a constantly rotated crank arm, a wheeled carriage, a pitman intermediate said crank arm and said carriage whereby uniform reciprocating movements are imparted to the latter, a shovel, means intermediate said carriage and said shovel whereby the latter is advanced and retracted, respectively, during the last half of the forward movement and the first half of the rearward movement of said carriage, means whereby said shovel is elevated to approximately upright position during the remainder of said rearward movement of the carriage and is lowered to ground-engaging position during the first portion of the forward movement of said carriage, and means whereby the direction of rotation of said crank may be reversed for effecting reversal of the direction of movement of said carriage at any point in the travel of the latter.

14. A loading machine embodying a carriage, means for imparting reciprocating motion to said carriage, a shovel having carrying arms pivoted thereto, rotary means intermediate said carriage and said carry-

ing arms whereby the latter and said shovel are advanced and retracted, respectively, during the last half of the forward movement and the first half of the rearward movement of said carriage, and means carried by said rotary means, whereby said shovel and said carrying arms are elevated to shovel-dumping position during the remainder of the rearward movement of the carriage and are lowered to load-collecting position during the first portion of the forward movement of said carriage.

15. A loading machine comprising a carriage, means for imparting reciprocating motion to said carriage, a shovel, means intermediate said carriage and said shovel and actuated to rotate by movement of the former whereby the latter is advanced and retracted, and means rigidly carried by said rotating means whereby said shovel is elevated to approximately upright position during a portion of the rearward movement of the carriage and is lowered to ground-engaging position during a portion of the forward movement of the carriage.

16. A loading machine comprising a constantly rotated crank arm, a carriage, a pitman intermediate said crank arm and said carriage whereby uniform reciprocating movements are imparted to the latter, a shovel, means intermediate said carriage and said shovel whereby the latter is advanced and retracted through movement of said carriage, means whereby said shovel is elevated to dumping position during the rearward movement of the carriage and is lowered to ground-engaging position during the forward movement of said carriage, and means whereby the direction of rotation of said crank may be reversed for effecting reversal of the direction of movement of said carriage at any point in the travel of the latter.

17. A loading machine comprising a frame, a member reciprocable on said frame, a shovel having supporting arms in pivotal relation to said member, constantly driven means whereby uniform reciprocating movements are imparted to said member for advancing and retracting said shovel, and means intermediate said member and said shovel arms whereby the latter are automatically moved to and from upright shovel-dumping position during the reciprocating movements of the parts.

In testimony whereof I affix my signature in presence of two subscribing witnesses.

JOHN H. HUHN.
